UNITED STATES PATENT OFFICE.

MAURICE KANE, OF CHICAGO, ILLINOIS, ASSIGNOR TO THE WARDER, BUSH-NELL & GLESSNER COMPANY, OF SAME PLACE, AND SPRINGFIELD, OHIO.

GRAIN-BINDER.

SPECIFICATION forming part of Letters Patent No. 499,838, dated June 20, 1893.

Application filed December 31, 1892. Serial No. 456,941. (No model.)

To all whom it may concern:

Be it known that I, MAURICE KANE, a citizen of the United States, residing at Chicago, county of Cook, and State of Illinois, have invented certain new and useful Improvements in Grain-Binders, which are fully set forth in the following specification, reference being had to the accompanying drawings, forming a part thereof.

10 The purpose of this invention is to provide improved and simple means for making the compressing power of the needle and compressor increase somewhat as the density of the bundle upon which they are operating increases under their compressing action, and bringing such power to the maximum at the point of culmination of the compressing action, and also to give these devices their greatest speed of movement when they are in 15 20 25 30 35 40 45 50 55 60 65 70 75 80 85 90 95 100 treat after the bundle has been completed and is wholly or partly ejected, while the continuance of the rotation is necessary simply to bring all the parts back to the initial position, the result of such construction being that without increasing the total length of time,—or length of travel of the machine over the ground,—occupied in each complete binding operation, a greater portion of time may be given to the binding processes requiring power and putting strain upon the mechanism, the time being made up by the greater speed of the movements which require slight power. The same expedient also gives the knotter-bill slower movement and the discharger more powerful movement, which is desirable.

In the drawings,—Figure 1 is a side elevation of so much of the mechanism of the grain binder as pertains to my invention, the deck, breast-plate, and binder frame being represented conventionally, the position of the parts being that of maximum compression of the bundle. Fig. 2 is a similar view, the position of the parts being that of rest, with the needle below the deck. Fig. 3 is a detail sectional rear elevation, showing the position of the knotter-bill and its actuating wheel when the parts are in the same position as shown in Fig. 1, section being made in a vertical plane rearward of the plane of the needle.

A is the binder deck.

B is the breast-plate.

C is the upright standard of the customary U-frame.

D is the needle.

55

E is the compressor.

F is the needle rock-shaft; F' the needle crank arm; F² the pitman or link connecting it to the binder main wheel G.

H is the main driving sprocket pinion which 6c communicates power to the binder by means of a chain whose position is indicated by the broken line J.

M is a tightener pulley which is mounted as hereinafter described.

65

E' is the lever arm of the compressor rock-shaft; E² the customary extensible link comprising the compressor spring E²⁰ which connects the crank arm E' to the lever E³ fulcrumed on the binder frame at e³, and carrying at the end opposite its connection with the link the cam roll E³⁰ which travels on the cam G' on the wheel G, which cam communicates the compressing movement to the compressor in substantially the customary manner. The distinguishing feature of this construction is that the binder main wheel G is journaled eccentrically on the binder frame, its shaft g being located at some little distance aside from the center of the wheel, as 75 seen in the drawings.

The center of construction of the wheel is indicated at g⁰ and in the position of the parts which is represented in Fig. 1 this center g⁰ is in the radius from the point of departure 85 or tangency of the drive chain J to the center of rotation or center of the shaft g. The position shown in this figure being that of maximum compression or culmination of the compressing action, it will be seen that the power 90 communicated from the main driving sprocket pinion H by means of the chain J to the binder main wheel G is greatest at this point because at this point the radius from the center of motion or pivotal center of the wheel G to the point at which the chain departs from the circumference of the wheel is longest—that is to say, the power is at this point applied with the greatest leverage and therefore with the slowest resultant rotary or angular movement of the wheel G. As the result of this arrangement the most rapid angular or rotary movement accompanied by the least power will be obtained when the wheel G is

in the opposite position. This is very nearly the position shown in Fig. 2; that is, very nearly the position at which the needle is at the lowest point. The needle will therefore 5 retreat more rapidly toward the latter part of its retreating movement on account of this construction, and the action of the compressor being controlled by the same wheel G will also be more rapid at the same stage. This 10 is as would be desired because at that stage the discharger K, which is of the ordinary construction and action, will have reached the bundle and will have commenced to impel it outward and will be rapidly gaining in 15 effectiveness in this respect as it approaches the point at which it is radial to the path of movement which it tends to give the bundle. But it is desirable that the powerful movement of the wheel G should not be lost until 20 the discharger has reached nearly to the most effective position for acting upon the bundle, or at least until it has passed the point of its minimum effectiveness. This point of minimum effectiveness is the point at which the 25 discharger first comes into contact with the bundle and which occurs within an eighth of a revolution of the wheel G after the needle has completed its advance and commenced its retreat. When the maximum 30 power of the wheel is attained at the climax of the needle's movement that power will have been but little diminished by the time an eighth of a revolution, which brings the discharger against the bundle, has been 35 made, and the discharger will thereby be able to operate powerfully to start the bundle outward from the position at which it has been formed, and where it is frequently quite tightly held between the deck and the breast- 40 plate. Evidently the most power is required just at this point to start the bundle, because not only is its inertia to be overcome but the tightness with which it is held diminishes as it moves outward, and by the time the wheel 45 G has made a quarter revolution from the position shown in Fig. 1, during half of which quarter the discharger has been moving the bundle, the resistance to the discharger's action will be practically passed and the more 50 rapid angular movement of the wheel G and of the discharger, which will by that time become noticeable, will be made against much decreased resistance, and within three eighths of a revolution after the needle starts back, 55 that is, from the position shown in Fig. 1, the bundle will be ejected and no further work remains to be done except to bring the parts back to their position of rest; and from this point on the movement is made with increasing 60 rapidity to the end or position of rest shown in Fig. 2.

The eccentric construction or journaling of the wheel G obviously makes it necessary to provide means for taking up and giving out 65 the chain J as the rotation of the wheel G proceeds and requires less or more chain to encompass it and the driving pinion H; and

for this purpose I mount the tightener M upon the end of a lever arm M', which is fulcrumed at m' on an arm C' of the frame, and 70 on the same arm a little farther grainward I mount the bracket M², through which the link or check-rod M³ extends, said check-rod being pivotally connected to the lever arm M' a little distance from the pivot of said arm toward the tightener pulley, and about the portion of the check-rod which protrudes through the bracket M² I coil the spring M⁴ and cause 75 it to be retained on the rod by the check-nut m⁴ screwed on to the end of said rod. It 80 will now be understood that the tendency of the spring M⁴ will be to hold the lever arm M' grainward and keep the tightener pulley M against the chain and take up all the slack which the latter affords; and that as the rotation of the wheel G causes it to require 85 more chain the slack will be taken up by that wheel, and the tightener M will be forced outward, and that the yielding of the spring M⁴ will permit it to move thus to the requisite 90 extent.

It will be understood that the maximum yielding of the spring and the extreme outward position of the tightener pulley and the nearest approach of the outer ply of the chain 95 to a direct line between the wheels over which it passes will not be reached at the position shown in Fig. 1 but at a position intermediate between that and the position shown in Fig. 2; and the spring M⁴ is represented as 100 having capacity for yielding sufficiently to bring the chain nearly to a straight line. On the other hand, the position of greatest slack of the chain or most inward position of the tightener M does not correspond to the position 105 shown either in Fig. 1 or in Fig. 2, but to a position subsequent to that of Fig. 1 and earlier than that of Fig. 2 in the rotary motion, and the spring M⁴ is designed to be understood as having further capacity for extension to take up more slack than is shown 110 taken up in either of the views.

A further advantage which is afforded by this construction of the binder main wheel G is that, without causing the entire binding 115 operation to occupy any greater time or extend over any larger portion of the travel of the machine, the action of the knotter-bill, while still kept perfectly timed with the other movements with which it must co-operate, is 120 made slower than it would be with the binder main wheel journaled centrally, the time being made up during the remainder of the rotation of the wheel before and after the knotter's movement. This, as will be well understood, makes it possible to use twine of less tensile strength and toughness. With a slow movement, a knot may be formed in twine which would break under a rapid movement. This feature will be apparent upon examination of Fig. 3, which shows the position of the knotter-bill at the stage of slowest movement corresponding to Fig. 1, the knotter-bill N being 125 just about to start as the gear segment P' 130

on the knotter-actuating wheel P comes into engagement with its pinion N'.

I claim—

1. In a grain binder, the binder main wheel G journaled eccentrically on the binder frame; devices which communicate motion to it by engagement with its eccentric periphery; the needle or binder arm and the mechanism through which it derives movement from the binder main wheel arranged to bring the needle to the end of its advance movement when the binder main wheel actuating devices are engaged with the portion of its periphery most remote from its center of rotation: substantially as set forth.

2. In a grain binder, the main wheel G, journaled eccentrically on the binder frame; the knotter and the mechanism through which it derives motion from the binder main wheel arranged to cause the knotter's rotation to be made while the devices which engage and drive the binder main wheel are operating upon that portion of its periphery which is more distant from its center of rotation: substantially as set forth.

3. In a grain binder, in combination with the needle rock-shaft and its crank arm, the binder main wheel and the link from the crank wrist thereof to the wrist of the needle crank arm, the main driving sprocket pinion and the chain which communicates power therefrom to the binder main wheel, said binder main wheel being journaled eccen-

trically, the center of construction being in the line from its center of motion to the point of tangency and departure of the drive chain when the center of motion is in line with the wrist of the needle crank arm and the crank wrist of the binder main wheel G: substantially as set forth.

4. In a grain binder, in combination with the main driving sprocket pinion H and binder main wheel G journaled eccentrically, the chain which communicates power from the former to the latter, the lever M' fulcrumed on the frame and carrying the tightener pulley, the link M³, spring M⁴, stop bracket M² and nut m⁴, connected and co-operating, substantially as set forth.

5. In a grain binder, the main wheel journaled eccentrically and carrying the bundle ejecting arm and the train by which said wheel is rotated, combined substantially as set forth, whereby the rotary movement of the wheel while the ejecting arm is performing its office is communicated to it by engagement with a portion of its arc on the side nearer the center of motion.

In testimony whereof I have hereunto set my hand, in the presence of two witnesses, at Chicago, Illinois, this 23d day of December, 1892.

MAURICE KANE.
